UNITED STATES PATENT OFFICE

HARRY R. WELCH AND CHARLES H. CASE, OF LOGANSPORT, INDIANA.

MECHANISM FOR AUTOMATICALLY CONTROLLING THE SPEED OF AND STOPPING ENGINES.

1,060,803.

Specification of Letters Patent.

Patented May 6, 1913.

Application filed April 11, 1912. Serial No. 690,013.

To all whom it may concern:

Be it known that we, HARRY R. WELCH and CHARLES H. CASE, citizens of the United States, residing at Logansport, in the county of Cass and State of Indiana, have invented certain new and useful Improvements in Mechanism for Automatically Controlling the Speed of and Stopping Engines, of which the following is a specification.

10 Our present invention pertains to mechanism for automatically controlling the speed of and stopping engines; and it contemplates the provision of a simple and inexpensive regulator and stop, readily applicable to the throttling governors of practically all types of engines, and calculated in the event of the throttling governor failing to perform its function, to quickly regulate the speed of the engine or bring the same to 20 a full stop, as the occasion demands.

Our novel regulator and stop is adapted to remain in a marking state for an indefinite period and when the necessity arises is positive and rapid in acting, as will be 25 fully appreciated from the following description and claims when the same are considered in connection with the drawings, accompanying and forming part of this specification, in which:

30 Figure 1 is a front elevation, parts broken away and in section. Fig. 2 is an end elevation. Fig. 3 is a horizontal section on line 3—3 of Fig. 1. Fig. 4 is a detail sectional view through the cylinder. Fig. 5 is a vertical transverse section on line 5—5 of Fig. 4.

Similar numerals designate corresponding parts in all of the views of the drawings referring to which:

1. is the casing of a throttling governor, 40 2 is the frame thereof.

3 is the vertically movable and rotatable stem equipped with centrifugal balls 4 and a circumferentially grooved portion 5.

6 is the miter gear through which rotary 45 motion is transmitted to the stem 3.

7 is a shaft provided with a belt wheel 8 and also with a miter gear 9 which latter is intermeshed with the gear 6, and 10 is a shaft equipped with a "Sawyer's" lever 11

50 and also with a bifurcated arm 12; the latter being arranged in engagement with the portion 5 of the stem 3.

In the present and preferred embodiment of our invention we provide a fixed cylinder 55 13 upon a suitable support 14, and in said

cylinder we arrange what may properly be denominated a piston 15. The said piston is provided with a rod 16 which is preferably connected thereto in a hinged or pivoted manner, and surrounding the said rod 60 16 is a strong expansion spring 17 which is interposed between the piston 15 and an abutment 18 within the cylinder at the end thereof adjacent the "Sawyer's" lever 11. Interposed between and connected to the 65 piston rod 16 and the upper end of the "Sawyer's" lever 11 is a flexible connection 19, preferably in the form of a chain as shown, and arranged alongside the exposed end of the piston rod 16 is a disk 20. 70 The said disk is supported to rotate upon a center 21 and is provided with a peripheral abutment 22. It will also be seen by reference to the drawings that the disk 20 is provided with a lateral pin 23, disposed 75 and adapted to rotate about its axis in a bearing 24 formed in the exposed portion of the rod 16.

At 25 on the support 14 is fulcrumed a trigger 26 which has an upper arm positioned to engage the abutment 22 of disk 20, and a lower and comparatively longer arm arranged to be engaged by the lower arm of the "Sawyer's" lever 11.

The practical operation of our invention 85 is as follows: The mechanism is set as shown in Figs. 2 and 4—i. e., the piston rod 16 is drawn outward against the action of the spring 17 and so as to rotate the disk 16 in the direction indicated by arrow in Fig. 90 2 until the abutment 22 of the disk is in front of and caught by the upper arm of the trigger 26. In the said positions the parts remain during the normal running of the engine. In the event, however, of 95 the drive belt (not shown) slipping off the wheel 8 or for any other reason the engine runs away the governor balls 4 will either rise, whereupon the governor stem 3 will be forced downward and through its circumferentially grooved portion 5 will depress the bifurcated arm 12 and pull inward and downward the upper arm of the "Sawyer's" lever 11. When this takes place the lower arm of the "Sawyer's" lever will force 100 outward the lower arm of the trigger 26 and in that way release the disk 20 from the upper arm of the trigger. Then upon the release of the disk 20 the strong spring 17 operates through the rod 16 and the chain 110

19 to pull the upper arm of the lever 11 toward the cylinder 13 and thereby raises the arm 12 and with it the stem 3, with the result that the steam is cut off.

5 It will be gathered from the foregoing that our novel device is simple and inexpensive in construction and embodies no delicate parts such as are likely to get out of order after a short period of use.

10 Having described our invention, what we claim and desire to secure by Letters Patent, is:

1. In mechanism for the purpose described, the combination of the stem of a 15 throttling governor, said stem having a circumferentially-grooved portion; a shaft; a bifurcated arm fixed on said shaft and engaging said circumferentially-grooved portion; a lever also fixed on said shaft and 20 having upwardly and downwardly extending arms; a cylinder; a piston movable in the cylinder and having a forwardly extending rod that extends beyond the forward end of the cylinder; a connection intermediate the piston rod and the upper arm of the lever; a spring incased in the cylinder and interposed between said piston and an abutment in the forward portion of the cylinder; a rotary disk connected off its 25 center with the exposed portion of the piston rod and having a peripheral abutment; and a pivoted trigger having an arm opposed to the disk abutment and also having an arm opposed to the lower arm of the 30 lever.

35

2. In mechanism for the purpose described, the combination of lever arms, a rotary disk having a peripheral abutment, a spring actuated mechanism connected with the disk off the center thereof and also 40 connected with one arm of the lever and adapted when the disk is released to exert pull on said arm, and a trigger having a portion opposed to the other lever arm and also having a portion opposed to the abutment of the disk.

3. The combination of a cylinder, spring, piston, piston rod, lever, connected with the piston rod, rotary notched disk connected with the piston rod, and trigger normally 50 engaging the disk to hold the spring against action and actuatable by the lever to release the disk and spring.

4. In combination with a governor, a stop attachment comprising a cylinder, a disk journaled beyond the cylinder, a spring pressed piston movably mounted in the cylinder, a rod connected to the piston and eccentrically connected to the disk, a trigger for holding the disk, and means adapted 55 to be operated by the governor to move the trigger to release the disk.

In testimony whereof we affix our signatures in presence of two witnesses.

HARRY R. WELCH.
CHARLES H. CASE.
